SUGAR BOWL SET

Anthony Rella, New York, N. Y.

Application May 28, 1952, Serial No. 19,920

Term of patent 3½ years

(Cl. D44—6)

To all whom it may concern:

Be it known that I, Anthony Rella, a citizen of the United States of America and resident of New York, county of the Bronx, and State of New York, have invented a new, original, and ornamental Design for a Sugar Bowl Set, of which the following is a specification, reference being had to the accompanying drawings forming part thereof.

In the drawing:

Fig. 1 is a front elevation of a sugar bowl set, showing my new design, the set consisting of a sugar bowl, a salt shaker, a pepper shaker, a filling spoon and a measuring cup;

Fig. 2 is a side elevation of the sugar bowl set;

Fig. 3 is a perspective view of the set with the lid thereof in an open position and the filling spoon placed therein; and

Fig. 4 is a rear elevation of the sugar bowl set without the spoon.

I claim:

The ornamental design for a sugar bowl set, as shown.

ANTHONY RELLA.
